J. S. HOLLANDER.

FENCEPOST.

APPLICATION FILED OCT. 25, 1921.

1,425,653.

Patented Aug. 15, 1922.

John S. Hollander, Inventor

By Richard B. Owen,

Attorney

UNITED STATES PATENT OFFICE.

JOHN S. HOLLANDER, OF DE QUINCY, LOUISIANA.

FENCEPOST.

1,425,653.

Specification of Letters Patent. Patented Aug. 15, 1922.

Application filed October 25, 1921. Serial No. 510,283.

To all whom it may concern:

Be it known that I, JOHN S. HOLLANDER, a citizen of the United States, residing at De Quincy in the parish of Calcasieu and 5 State of Louisiana, have invented certain new and useful Improvements in Fenceposts, of which the following is a specification.

This invention relates to fence posts and has for its object the production of a simple 10 and efficient means for fastening fence wire thereto.

Another object of this invention is the production of a quickly attaching means for attaching fence wire to a post.

15 With these and other objects in view, this invention consists of certain novel constructions, combinations and arrangements of parts as will be hereinafter fully described and claimed.

20 In the drawings:

Figure 1 is a perspective view of the body of the fence post, and the clamping bar being removed therefrom.

Figure 2 is a vertical section through the 25 clamping bar, shown in position upon the body of the post.

Figure 3 is a section taken on line 6—6 of Figure 5.

Figure 4 is a detail perspective view of the 30 anvil plate which is used for driving the body of the post into the ground.

By referring to the drawings, it will be seen that 1 designates the body of the post which is provided with a rear vertically extending 35 reinforcing plate 2, and a front reinforcing plate 3, these plates being formed integral with the body 1 of the post. The body is provided with a beveled lower edge 5 and the plate 2 is provided with a beveled lower edge 4, the plate 3 also being provided 40 with a beveled lower edge 6, as shown in Figure 4. A driving shoulder 7 is formed upon the body 1 of the post, and this shoulder is bent upwardly to form a vertical bracing rib 8. A forwardly extending web is formed upon the rib 8, and a plurality of wire receiving notches 10 are formed upon or in the forward edge of the web 9.

A clamping strip 11, which is V-shaped in 50 cross section, fits over the forward edge of the web 9 and clamps the wire 12 in the notches 10 formed in the web 9. The lower end of the clamping strip 11 is tapered to fit in the V-shaped socket 13, formed at the 55 upper end of the plate 3. The clamping

plate 11 is provided with an overhanging lip 14, having an aperture 15 adapted to fit over the threaded bolt 16. The bolt 16 is arranged at the same angle to the body of the post, as the side wall of the notch 13, to facilitate the passing of the clamping strip over the bolt 16. A nut 17 is threaded upon the bolt 16, this bolt being threaded only on one side thereof. The fence wire 12 is wedged into the clamping plate as shown in Figure 7, when the plate 11 is forced over the wire and the forward edge of the web 9.

An anvil plate 17 is provided with a V-shaped aperture 18, which is adapted to fit over the web 9 and the rib 8, the anvil plate 17 being adapted to rest upon the driving shoulder 7 of the post 1. The anvil plate 17 is removable, and is only used while driving the post into the ground.

From the foregoing description, it will be seen that a very simple and efficient post has been produced for supporting fence wire, and it should be understood that the post may be utilized for the construction of any desired form of fence. For instance, poultry wire may be attached to the posts by attaching the wire to the top notches of the posts, and the clamping plate 11 will firmly secure the wire to the post. It should also be understood that certain detail changes may be made in the device without departing from the spirit of the invention, so long as these changes fall within the scope of the appended claims.

Having described the invention, what is claimed is:

1. A fence post comprising a body having right angularly extending reinforcing plates formed upon the edge thereof, a driving shoulder formed upon the body and terminating in a bracing rib, a web formed upon the forward face of the rib, a clamping plate adapted to fit over the front edge of the web for securing fence wire thereto, said body provided with a V-shaped notch upon the front edge thereof, the clamping plate having a tapered lower edge fitting in the V-shaped notch, said clamping plate provided with an overhanging end, and a bolt formed upon the body engaging the overhanging end for locking the clamping plate upon the body.

2. A fence post comprising a reinforced vertical section provided with wire receiving notches, said post having near the ground

line an inwardly extending angular notch, the upper end of said post provided with an integral screw threaded bolt extending from the top of said post at an angle substantially the same as the angle of said notch, a clamping bar adapted to co-operate with said post, terminating at its lower end in a wedge, and having at its upper end a perforated overhanging portion, said post adapted when

assembled to positively cam the clamping bar into position and to releasably lock said clamping bar in locking position.

In testimony whereof he affixes his signature in presence of two witnesses.

JOHN S. HOLLANDER.
